UNITED STATES PATENT OFFICE.

GEORGE S. WITHAM, JR., OF HUDSON FALLS, NEW YORK, ASSIGNOR OF ONE-HALF TO
GEORGE S. WITHAM, SR., OF HUDSON FALLS, NEW YORK.

BUR FOR TREATING GRINDSTONES.

1,255,494.

Specification of Letters Patent.

Patented Feb. 5, 1918.

Application filed August 17, 1917. Serial No. 186,726.

To all whom it may concern:

Be it known that I, GEORGE S. WITHAM, Jr., a citizen of the United States, residing at Hudson Falls, in the county of Washington and State of New York, have invented certain new and useful Improvements in Burs for Treating Grindstones, of which the following is a specification.

In the preparation of grindstones for the manufacture of paper pulp difficulties have been experienced in so operating the bur employed in dressing the stone as to produce the desired cut or cuts in the stone as often the teeth of the bur cut too deeply into the stone or irregular incisions are made which result in lack of uniformity in the pulp.

One feature of my invention consists in providing means for regulating the depth of cut made by the bur. I accomplish this by providing the bur with a circular relatively smooth bearing surface of less diameter than the circular series of teeth with which the bur is provided. By this construction the teeth are made to project a sufficient distance from the bur to produce the desired depth of cut while the bearing surface limits the penetration of the teeth into the stone. Preferably such a bearing surface is provided on each side of the teeth and preferably also the bearing surfaces are formed on rings which are detachably connected with that portion of the bur carrying the teeth because in this way rings of varying thicknesses may be used and any desired depth of cut may be obtained. In order to produce various qualities of pulp grindstones of different kinds must be employed and often the depth of cut determines the quality of the pulp obtained. By providing the bur with detachable bearing rings the same bur may be employed for producing different grades of pulp, the depth of cut being determined by the thickness of the ring.

My improvements are illustrated in the accompanying drawings, in which:

Figure 1 is a top plan view of a grindstone bur equipped with my improvements, the frame or holder for the bur being partly broken away.

Fig. 2 shows a side elevation of the same.

Fig. 3 shows a vertical central section of another form of bur embodying my improvements.

Fig. 4 shows a front elevation of the same.

Fig. 5 shows a side elevation of the bur

shown in Figs. 3 and 4, parts being broken away in order to better show the construction.

In each case the bur proper is indicated at 1 and it is provided with teeth 5 of suitable construction to dress the stone. The bur may be suitably mounted in a frame or holder 10 carrying a mandrel 3, to which the bur may be attached in any suitable way. I provide the bur with a circular bearing 60 surface which, as will be observed by reference to Fig. 1, is of less diameter than the outer periphery of the circular series of teeth formed on the bur. This bearing surface may be produced in various ways. In 70 Figs. 1 and 2 I have shown rings 2 which are attached in any suitable way to the bur or to the shaft or mandrel carrying the bur. It is preferable however that these rings be made detachable. In this way they can be 75 separately formed and made of any desired diameter. It is obvious also that by the use of rings of different diameters the depth of cut may be varied on any bur and such rings may be applied to various kinds of burs 80 without necessarily altering the construction of such burs. While I prefer to employ separate rings I may embody my invention in the construction shown in Figs. 3, 4 and 5, in which case the bearing surfaces are 85 formed in the body of the bur as indicated at 20. In this case also the bearing surface is circular and is of less diameter than that of the periphery of the teeth with which the body of the bur is provided. Such bearing 90 surfaces may be easily formed on various kinds of burs and may be made of any desired diameter.

It will be observed that while the bearing surface is of less diameter than that of the 95 periphery of the teeth with which the body of the bur is provided, the diameter of such bearing surface is greater than the diameter at the inner ends of the teeth.

I claim as my invention:

1. A cylindrical bur for treating grindstones provided with a circular series of cutting teeth on its periphery, and with a circular relatively smooth bearing surface the diameter of which is considerably less than the periphery of the toothed portion of the bur but whose diameter is greater than the diameter at the inner ends of the teeth.

2. A cylindrical bur for treating grindstones provided with a circular series of 110

cutting teeth on its periphery, and with a circular relatively smooth bearing surface on each side of the toothed portion of the bur the diameter of which is considerably less than the periphery of the toothed portion of the bur but whose diameter is greater than the diameter at the inner ends of the teeth.

3. A cylindrical bur for treating grind-
10 stones provided with a circular series of

cutting teeth on its periphery, and with a detachable ring having a relatively smooth peripheral bearing surface the diameter of which is considerably less than the periphery of the toothed portion of the bur but 15 whose diameter is greater than the diameter at the inner ends of the teeth.

In testimony whereof, I have hereunto
subscribed my name.

GEORGE S. WITHAM, JR.
